DESIGN FOR A HOUSING FOR BATHTUB FITTINGS

Horace S. Smith, Kinsman, Ohio, assignor to The Glauber Brass Manufacturing Company, Kinsman, Ohio, a corporation of Ohio

Application July 18, 1940, Serial No. 93,773

Term of patent 3½ years

To all whom it may concern:

Be it known that I, Horace S. Smith, a citizen of the United States and a resident of Kinsman, in the county of Trumbull and State of Ohio, have invented a new, original, and ornamental Design for a Housing for Bathtub Fittings, of which the following is a specification, reference being had to the accompanying drawing, forming a part thereof, in which—

Fig. 1 is a plan view, Fig. 2 an end elevation, and Fig. 3 a front elevation, respectively, of a housing for bathtub fittings showing my new design.

I claim:

The ornamental design for a housing for bathtub fittings, as shown.

HORACE S. SMITH.
